Primary Examiner — Keli L Hill*Assistant Examiner* — Sara S Sahneh(74) *Attorney, Agent, or Firm* — Patterson + Sheridan, LLP(57) **CLAIM**

The ornamental design for a digital tire gauge, as shown and described.

DESCRIPTION

FIG. 1 is a top left front perspective view of a digital tire gauge showing our new design;

FIG. 2 is a top right rear perspective view thereof;

FIG. 3 is a bottom left front perspective view thereof;

FIG. 4 is a bottom right rear perspective view thereof;

FIG. 5 is a top plan view thereof;

FIG. 6 is a left elevational view thereof;

FIG. 7 is a bottom plan view thereof;

FIG. 8 is a right elevational view thereof;

FIG. 9 is a front elevational view thereof; and,

FIG. 10 is a rear elevational view thereof.

The portions of the digital tire gauge shown in broken lines form no part of the claimed design.

1 Claim, 9 Drawing Sheets(56)
